CLAIM

The ornamental design for an adapter for sparkling soda machine, as shown and described.

DESCRIPTION

FIG. 1 is a first perspective view of an adapter for sparkling soda machine showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The broken lines shown in the drawings depict portions of the adapter for sparkling soda machine that form no part of the claimed design. The short dash long dash broken lines depict the boundary of the enlarged view and form no part of the claimed design.

1 Claim, 9 Drawing Sheets
